PLUMBING FIXTURE

Jessie Kennison, Madison, Wis.

Application May 23, 1932. Serial No. 613,097

3 Claims. (Cl. 4—166)

This invention relates to the broad class of household plumbing fixtures and has more specific reference to certain improvements and refinements embodied in the construction of bath 5 tubs, sinks, and wash basins and the like.

In the present-day equipment and accessories these particular structures are generally enameled or porcelain coated. Moreover as a general rule, white or porcelain of light colored shades is employed. Hence, it has been observed that water 10 running or dripping from faucets and spigots frequently form a mineral stain of an unsightly and ugly character. These stains, it will be admitted, are positively difficult to remove. Hence, 15 wash basins, tubs and the like take on an unsanitary appearance which is undesirable to say the least.

The purpose of the present invention is to manufacture tubs, basins and the like with inlaid 20 portions arranged at predetermined points, said inlaid portions being of stainless material for example chromium plated sheet metal.

More specifically stated, the novelty of the invention is predicated upon a faucet equipped water 25 receptacle having chromium plate inlaid areas extending from points within the vicinity of the discharge ends of the spigots or faucets to the drain plug hole in order to provide stainless highly polished runways between the faucets or 30 spigots and the drain in order to overcome the objections mentioned.

Referring now to the accompanying pictorial drawings:—

Figure 1 is a cross sectional view through a 35 modern type bath tub embodying the invention.

Fig. 2 is a top plan view of Fig. 1.

Fig. 3 is a similar sectional and elevational view through a double faucet equipped wash basin showing the invention installed.

Fig. 4 is a plan view of the structure seen in Fig. 3.

Fig. 5 is a detail section taken approximately on the plane of the line 5—5 of Fig. 3.

In Figs. 1 and 2 the conventional porcelain coated bathtub is denoted by the numeral 6 and this is of usual construction and includes a spigot or faucet 7 having operating handles for the valves, the handles being distinguished by the numerals 8 and 9. The drain pipe is indicated at 10 and the drain pipe top is denoted by the numeral 11. The invention comprises the chromium plated inlay 12 which extends from the top of one end wall of the tub to the bottom 55 where it gradually diminishes in width and proportions and where it extends at right angles

along the bottom of the tub and terminates in a disk-like portion 13 having a neck 14 extending down into the drain opening of the tub.

The numeral 15 merely designates the grid of the overflow slot which is provided as is usual. The spigots are mounted in the tub end in the usual way and extend through the relatively wide upper end portion of the perpendicular part of the inlay. The inlay is arranged in a groove provided therefor and is flush with the porcelain facing of the tub.

In Figs. 3 to 5 inclusive, the numeral 16 designates an ordinary basin having the customary pair of spigots or faucets 17 and 18 and drain pipe 19. The inlay here comprises a pair of branches 20 and 21 extending from the faucets downwardly to the drain openings where the branches join with a slightly enlarged disk-like central portion 22 having a drain neck 23. These branches cooperate defining the customary paths followed by the streams of water ejecting from the faucets when the faucets are turned on. These are the faucets of the ordinary basin which would be subject to tarnishing and staining.

In Fig. 5, it is evident that the chromium-faced inlay is fitted and securely anchored in the groove so that it is flush with the "plain coated" surface of the basin. The idea is fundamentally the same in both forms of the invention.

The gist of the invention is predicated upon the construction of an appliance of the class described wherein said appliance is generally porcelain-coated throughout its major visible and effective surface as is usual in the construction of bath tubs, basins, sinks and the like. Incidentally, in the succeeding claims, the term "receptacle" is used to comprehend any of these various types of bathroom and kitchen appliance fixtures. The porcelain receptacle is formed at a predetermined point with a groove in which an inlay is positioned, the inlay being of stainless metal preferably chromium-plated or coated sheet material. The inlay is of a proportion to provide the requisite flush surfaces and of a width and length to serve as an anti-splash backing for the spigots, and to define a longitudinal runway extending from the spigots to the drain or outlet.

In other words, the inlay takes in an area of the receptacle such as might otherwise be subjected to staining and tarnishing from the mineral elements of incoming water, particularly in the case of dripping spigots.

It is thought that the description taken in connection with the drawings will enable a clear

understanding of the invention to be had. Therefore, a more lengthy description is thought unnecessary.

While the preferred embodiment of the invention has been shown and described, it is to be understood that minor changes coming within the field of invention claimed may be resorted to if desired.

Having thus described my invention, what I claim as new is:—

1. In a structure of the class described, a bath tub of the usual porcelain faced type, said bath tub being provided with a draining opening, a drain pipe in communication with said opening, one end wall and the adjacent portion of the bottom of the tub being grooved, a chromium plated inlay arranged in said groove and flush with the remaining surfaces of the tub, said inlay surrounding the drain opening and having a neck depending into the opening in alignment with the drain pipe, and spigots mounted in the end wall of the tub and having a discharge faucet cooperating with the inlay.

2. A wash basin comprising a receptacle of conventional form having its major portion por-

celain coated, said receptacle being formed in the center of its bottom with a drain opening, spigots mounted on the receptacle in customary spaced relationship, that portion of the receptacle leading from the drain opening to the spigot being formed with grooves, and a chromium faced inlay arranged in the groove and including branch portions extending from the respective spigots downwardly to the drain opening, that portion of the inlay surrounding the drain opening being enlarged and formed with a neck depending into the drain opening.

3. In combination with bathing apparatus, a porcelain water storing receptacle including a bottom wall and an upstanding side wall, said receptacle also having a water supply spigot, a drain in the bottom wall beneath the spigot, a non-corrosive and stainless inlay seated in the receptacle flush with and conforming to the surface thereof, said inlay surrounding the drain in the bottom wall and extending into the upstanding side wall in proximity to the mouth of the spigot.
